TROUGH SUPPORTING MEANS

Charles P. Boyd, Kennett Square, Pa.

Application February 29, 1940, Serial No. 321,535

3 Claims. (Cl. 248—48.1)

My invention relates to trough supporting means and it relates more particularly to means for supporting troughs, such as eaves troughs which are subject to intermittent light and heavy loads and extreme variations in stresses and strains due to vagaries of the weather.

In the construction and assembly of eaves troughs, because of the cantilever construction of the trough and support assembly, it is essential that the lightest material be used. Yet the trough must be so mounted despite its lightweight and cantilever construction as to enable it to carry relatively heavy loads, as for instance, when it is filled with rain-soaked leaves and other debris, or when it is filled with ice. This problem becomes particularly acute in view of the varying stresses and strains to which the trough and its supporting means are subjected due to their exposure to strong winds and the eddy currents induced thereby, the expansion of ice within the trough acting against the tendency of the trough and its supports to contract due to cold, and the expansion and contraction due to vagaries of weather temperature.

Moreover, drainage of various elements together with the presence of air and water results in the corrosion of the trough and its supporting structure, thereby tending in time to weaken the trough and its supporting structure, and increasing the importance that destructive stresses and strains therein be reduced to a minimum.

In the past, various attempts have been made to solve these problems inherent in the trough-support assembly. Thus, sheet metal supports have been used, but have been generally undesirable due to their lack of strength and stability. Cast metal supports have been used but have been found too rigid and apt to crack under varying strains and stresses with respect to the trough, moreover, they have been too expensive. More recently, attempts have been made to use supports made of channel metal which is not as apt to crack under strain as the cast metal, and the cost of the raw material of which is less expensive. However, the channel metal supports of the prior art relied for their supporting sections upon unduly distorted or fatigued portions of the metal, thereby materially weakening the support. Moreover, the type of distortion hitherto in use is of an expensive nature, and tends materially to increase the price of the support until there is not much, if any, difference in cost between the channel metal support and the expensive cast metal support.

It is an object of my invention, therefore, to provide a supporting means for a trough, which shall be of maximum strength and durability, and wherein the effect of stresses and strains imposed by the weather and the varying demands

upon the strength of the trough and its supports, in use, shall be minimized.

It is another object of my invention to provide means for securing the trough to the supporting structure whereby the varying strains, normally imposed in use, of one with respect to the other, will be absorbed while inhibiting fatigue or undue stress of the securing means, operably to ensure a longer life to the whole structure.

10 A further object of my invention is to provide a trough supporting means which shall be inexpensive to make and very easy and quick to assemble and disassemble, as well as efficient in operation.

15 With the above and other objects in view, my invention consists of a trough supporting means comprising a channeled metal beam or similar structure comprising spaced parallel flanges having a web disposed therebetween; means for securing said beam to a structure; a trough supporting arm comprising a channeled metal bar having parallel flanges and a web disposed therebetween; said bar having a shank formed at one end, a recess formed at the other end, and a bed disposed therebetween; said shank end comprising a limiting stop adapted to abut against one edge of a trough; means for interlocking at least one flange of said beam with at least one flange of said bar operative to prevent displacement of said bar in a downward direction about the shank end as a pivot, and means for retaining said flanges in interlocked condition.

20 My invention also consists of the combination of the trough supporting means hitherto described, with a preformed, resilient, trough-securing means comprising a base member, a plurality of spaced hooks adapted to embrace a beaded edge of a trough disposed in said bed with the opposed edge of said trough abutting against said limiting stop, each hook having extended from one end thereof, and at a substantial angle thereto, a spacer member, said spacer member and said hook lying substantially within one plane, a base disposed between said spacer members and spaced 25 from said hooks, and curved connecting arms extending from the ends of said hooks opposed to the spacer member ends thereof and adapted to engage the recessed end of said trough-supporting arm.

25 My invention further consists of a trough securing means comprising spaced hooks adapted to embrace a trough bead, a handle member disposed between said hooks and spaced therefrom by legs projecting from said hooks, each of said 30 legs projecting from one of said hooks in a manner to form a curved node at the juncture thereof; and connecting means projecting from said hooks and adapted resiliently to connect said hooks with a trough supporting arm or "circle," 35 said nodes being adapted to interlock with, and

ride over said bead in the assembly of said securing means, trough and circle.

For the purpose of illustrating my invention, I have shown in the accompanying drawings forms thereof which are at present preferred by me, since the same have been found in practice to give satisfactory and reliable results, although it is to be understood that the various instrumentalities of which my invention consists can be variously arranged and organized and that my invention is not limited to the precise arrangements and organizations of the instrumentalities as herein shown and described.

Referring to the drawings, in which like reference characters indicate like parts:

Figure 1 represents a side elevational view of a trough and trough supporting means embodying my invention.

Figure 2 represents an opposed side elevational view of a trough supporting means embodying my invention.

Figure 3 represents a rear elevational view of a "circle" embodying my invention.

Figure 4 represents a perspective view of a trough-securing clip embodying my invention.

Figure 5 represents a front elevational view showing one manner of assembling the trough and trough supporting means embodying my invention.

Figure 6 represents a front elevational view illustrating the first stage of a modified method of assembling the trough and trough supporting means embodying my invention.

Figure 7 represents a side elevational view of the stage of assembly illustrated in Figure 6.

Figure 8 represents a front elevational view illustrating the second stage of the modified method of assembling illustrated in Figure 6.

Figure 9 represents a side elevational view of the stage of assembly illustrated in Figure 8.

According to my invention, I provide a beam or shank 20, preferably formed of channeled metal comprising spaced parallel flanges 21 and 22 projecting from one face of a web 23, and defining a channel 24. The beam 20 is secured, in a preferably substantially vertical position, to a building adjacent or just below the roof thereof, by any suitable means such as the screws 25, with the web 23 disposed substantially perpendicular to the side wall of the building.

A trough securing arm or "circle" 26 is provided, and preferably formed of channel metal of substantially the same cross-sectional size and shape as those of the beam 20, with an inner flange 27, an outer flange 28 spaced therefrom, and an intermediate web 29, defining a channel 30. The circle 26 is curved in the plane of its web 29 to form a shank end 31, a recessed end 32 and a trough receiving bed 33 therebetween. The curvature of the circle is such as to conform generally to that of a trough 34 having a straight edge 35 and a beaded edge 36.

The shank 31 of the circle 26 is preferably uncurved, but comprises instead a straight inner flange portion 37 adjacent the uncurved web portion 38. The outer flange opposite the straight inner flange portion 37 is swaged outwardly until it is flush with the channel face 39 of the web 38, operatively to broaden the width of the shank to an additional width equal to the width of the flange 27.

A channel 40 is swaged downwardly through the outer flange 28 with the forward wall 41 thereof substantially coplanar with the rearward face 42 of the straight inner flange portion 75

37, the bed thereof coplanar with the channel face 39 of the web 29, and the rearward wall 43 thereof spaced from the forward wall 41 a distance equal to the thickness of the base of the flange 21 of the beam or shank 20.

The forward half of the web 38 projects upwardly above the upper edge of the straight inner flange portion 37 of the circle, and is curved forwardly and then downwardly to form a hook 10 44 having an abutting edge or limiting stop 45 adapted to bear against the straight edge 35 of the trough 34. The rearward portion 46 of the base of the hook 44 is swaged to form a bead or node 47 projecting in the same direction as the flange 37, and spaced therefrom a distance equal to the thickness of the base of the flange 21 of the beam or shank 20.

Equally spaced height adjustment orifices 48 are centrally disposed in the web 23 of the beam or shank 20 and extend a substantial distance therealong. Similar orifices 49 are disposed in the web 38 of the circle 26 along an axis spaced from the inner wall 42 of the flange 37 a distance equal to the distance between the outer wall 50 and the axis of the orifice 48 of the beam 20, and are spaced from each other in a manner to permit a vernier adjustment between the height of the circle 26 and that of the beam 20 when the two are assembled. Thus, when four orifices 49 are used on the circle 26 and spaced with respect to the orifices 48 of the beam 20 in the ratio of five to four, and the beam orifices 48 are spaced one-half inch apart, vernier adjustment may be made of one-eighth inch intervals.

The recessed end 32 of the circle 26 terminates a short distance below the bead 36, and comprises a recess 51 cut rearwardly and upwardly through the outer flange 28 and the web 29 of the circle 26, operably to form a hook 52 adapted to interlock with a trough-securing means such as the clip 53.

The clip 53 is preferably formed of one piece of resilient spring wire, and comprises a base or handle member 54 having extending in one direction from the ends thereof, and preferably perpendicular thereto, parallel legs 55 and 56 serving also as spacer members. Spaced, parallel bead-embracing hooks or clamps 57 and 58 are respectively joined at one end thereof, to the spacer members 55 and 56 by downwardly projecting, curved nodes 59 and 60 respectively; said spacer members being preferably at substantially right angles to their respective hooks, and the leg 55, node 59 and hook or clamp 57 being preferably coplanar, and the opposed leg 56, node 60, and clamp 58, being similarly coplanar.

Substantially co-radially curved, coplanar connecting members or arms 61 and 62, overlapping at a portion of their respective arcs, are connected at their respective ends, opposed to the overlapping ends thereof, to the clamps 57 and 58; the plane of said arms 61 and 62 being preferably perpendicular to either of said leg, node and hook planes. The center of the arc of the cooperating arms 61 and 62 is preferably disposed along the median plane between the hooks 57 and 58 and between the axis of curvature of said hooks and the periphery defined by the legs 63 and 64 thereof adjacent the respective nodes 59 and 60.

It will be understood that although the clip 53 may be made of materials other than spring wire, it is preferred that it be made of spring wire of circular cross-section and that the com-

ponent parts of the clip be integral and joined by curved junctures.

In operation, the circle 26 is mounted on the beam or shank 20 with the flanges 37 and 28 of one directed toward the flanges 21 and 22 of the other. The rearward face 42 of the straight flange 37 of the circle 26 is brought to bear against the forward face 50 of the beam flange 21, and the extended portion of the web 38 is brought to bear against the rearward beam flange 22. In this position, the forward beam flange 21 extends through the channel 40 and is snugly embraced by the walls 41 and 43 thereof. Spaced a substantial distance from the channel portion 40, the flange 22 is again embraced by the bead or node 47 of the circle web 38, in one direction, and by the extended flange 37 in the opposed direction. The circle is slid along the beam until the proper orifices are in registry for defining the desired height of the circle, and a bolt 65 is passed therethrough and secured in place by any suitable nut 66. The bolt and nut serve to maintain the desired height of the circle and to retain the circle and beam in interlocked condition. The cantilever stresses and strains however are sustained primarily not by the bolt, but by the interlocked flanges, which prevent downward rotation of the circle, and thus the tendency of the bolt to shear is minimized.

The trough 34 is thereafter mounted in the "circle" 26 with the straightedge 35 abutting the lower edge 45 of the hook 44, and with the bead 36, in general registry with the recessed end 32 of the circle. The connecting arms 61 and 62 of the clip 53 are slid into the recess 51 of the end 32 of the circle 26, with the nodes 59 and 60 resting on the bead 36. The hooks or clamps 57 and 58 are then brought into interlocked engagement with the bead 36 by urging them upwardly and rearwardly against the resilient tension of the connecting arms 61 and 62, as more clearly shown in Figure 5.

However, where the spring tension is great, as when the distance between the bead and the recess is long, I prefer to assemble the clip, circle and bead in the following manner: The clip in the recess 51 is tilted while light rearward pressure is brought to bear on one hook, such as the hook 57, until the node 59 is initially interlocked with the upper periphery of the bead 36, as more clearly shown in Figures 6 and 7. Continued light upward and rearward pressure is exerted against the hook 57, in order to maintain the node 59 in interlocked condition with the bead 36, while stronger upward and rearward pressure is exerted against the hook 58 until the node 60 is interlocked with the upper periphery of the bead 36. In this position, the node 59 is now interlocked with the rearward portion of the bead 36, all as more clearly shown in Figures 8 and 9. But slight pressure is now required against the hook 58 to cause the node 60 to pass over the crest of the bead 36, and to permit the tension of the connecting arms 61 and 62 to cause the nodes and hooks to slip into place, snugly to embrace the bead 36. It will be noted in this procedure that a considerable portion of the tension of the connecting arms is borne by the rounded nodes cooperating with the bead, thereby requiring but little pressure on the part of the operator to bring the clip into snugly interlocking engagement with the trough bead.

It will be noted further that the base of the

clip being disposed posterior of the bead, where no variation in position occurs once the trough and support are assembled and in use, and the overlapping curved arms being disposed in the recess, the clip is in a position constantly and resiliently to take up all variation in distance between the bead and the recess, due to the inability of the vernier adjustment of the orifices 48 and 49 to provide for all possible variation in heights, and the vagaries of the weather, temperature, wind, etc. Moreover, the curvature of the arms about the center hereinbefore described results in a constant presentation to the hooked recess 51 of oppositely hooked arms 61 and 62, regardless of the tension or the distance between the recess 51 and the bead 36. Furthermore, the construction of the clip is such that strains and stresses are substantially evenly distributed throughout with a minimum of twisting stress or torque. Thus, the clip acts constantly to absorb stresses and strains of the trough relative to the circle, yet such stresses and strains are so evenly absorbed by the clip as to minimize the possibility of crystallization and fatigue; thereby assuring a longer life to the entire structure.

When it is desired to remove the clip, it is but necessary to pull forwardly and upwardly on the handle member or base 65, whereupon the hooks 57 and 58 rise until their nodes 59 and 60 ride upon and over the bead 36 until the clip is disengaged therefrom.

The circle and beam may be made of any desired material such as iron, copper, mild channel steel, etc.

I am aware that the invention may be embodied in other specific forms without departing from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what I claim as new and desire to secure by Letters Patent is:

1. A trough securing clip comprising spaced hooks, each hook having extending from one end thereof and at a substantial angle thereto, a spacer member, said spacer member and said hook lying substantially within one plane, a base disposed between said spacer members and spaced from said hooks, and curved connecting arms extending from the ends of said hooks opposed to the spacer member ends thereof and adapted to engage a trough supporting arm.

2. A trough securing clip comprising spaced hooks adapted to embrace a trough bead, a handle member having a leg and disposed between said hooks and spaced from one of said hooks by means of said leg, a curved node formed at the juncture of said leg and said hook; and connecting means adapted resiliently to secure a trough supporting arm to one of said hooks; said node being adapted to interlock with, and ride over said bead.

3. A trough securing clip comprising spaced hooks, a base member disposed between said hooks, a spacer member disposed intermediate said base member and one of said hooks, and connecting arms extending from said hooks and adapted to engage a trough supporting arm.
